[57] CLAIM

The ornamental design for a safety jack for mobile homes and trailers, as shown and described.

DESCRIPTION

FIG. 1 is a front elevational view of a safety jack for mobile homes and trailers showing my new design; FIG. 2 is a right side elevational view thereof; FIG. 3 is a left side elevational view thereof; FIG. 4 is a top plan view thereof; FIG. 5 is a bottom plan view thereof; FIG. 6 is a front elevational view of a second embodiment of the safety jack for mobile homes and trailers; FIG. 7 is a right side elevational view of FIG. 6; FIG. 8 is a left side elevational view of FIG. 6; FIG. 9 is a top plan view of FIG. 6; and FIG. 10 is a bottom plan view of FIG. 6. The rear views of FIGS. 1 and 6 are mirror images of the front views. The broken lines showing an I-beam and pier is for illustrative purposes only and forms no part of the claimed invention.

FIG. 1

FIG. 2

FIG. 4

FIG. 5

FIG. 3

FIG. 9

FIG. 7

FIG. 8

FIG. 10
